(57) **ABSTRACT**

An adjustment element for an article of footwear includes a bladder having a barrier layer defining an interior void and a compressible component disposed within the interior void and including a lattice structure defining a plurality of reliefs formed in the lattice structure, the compressible component operable between an expanded state when the interior void includes a first pressure and a contracted state when the interior void includes a second pressure.

VACUUM TRANSFORM UPPER FOR
ARTICLE OF FOOTWEARCROSS REFERENCE TO RELATED
APPLICATIONS

This application claims priority under 35 U.S.C. § 119(e) to U.S. Provisional Application No. 63/174,763, filed on Apr. 14, 2021. The disclosure of this prior application is considered part of the disclosure of this application and is hereby incorporated by reference in its entirety.

FIELD

The present disclosure relates generally to an adjustment device for an article of apparel or footwear.

BACKGROUND

This section provides background information related to the present disclosure which is not necessarily prior art.

Articles of apparel such as garments and headwear and articles of footwear such as shoes and boots, typically include a receptacle for receiving a body part of a wearer. For example, an article of footwear may include an upper and a sole structure that cooperate to form a receptacle for receiving a foot of a wearer. Likewise, garments and headwear may include one or more pieces of material formed into a receptacle for receiving a torso or head of a wearer.

Articles of apparel or footwear are typically adjustable and/or are formed from a relatively flexible material to allow the article of apparel or footwear to accommodate various sizes of wearers, or to provide different fits on a single wearer. While conventional articles of apparel and articles of footwear are adjustable, such articles do not typically allow a wearer to conform the shape of the article to a body part of the wearer. For example, while laces adequately secure an article of footwear to a wearer by contracting or constricting a portion of an upper around the wearer's foot, the laces do not cause the upper to conform to the user's foot. Accordingly, an optimum fit of the upper around the foot is difficult to achieve.

DRAWINGS

The drawings described herein are for illustrative purposes only of selected configurations and are not intended to limit the scope of the present disclosure.

FIG. 1A is a lateral side view of an example of an article of footwear according to the present disclosure, where the article of footwear is in a relaxed state;

FIG. 1B is a lateral side view of the article of footwear in FIG. 1A, where the article of footwear is in a contracted state;

FIG. 2A is a front perspective view of the article of footwear of FIG. 1A, where the article of footwear is in the relaxed state;

FIG. 2B is a front perspective view of the article of footwear of FIG. 1B, where the article of footwear is in the contracted state;

FIG. 3 is a rear perspective view of the article of footwear of FIG. 1A;

FIG. 4A is a cross-sectional view of the article of footwear of FIG. 2A, taken along Line 4A-4A in FIG. 2A;

FIG. 4B is a cross-sectional view of the article of footwear of FIG. 2B, taken along Line 4B-4B in FIG. 2B;

2

FIG. 5A is a perspective view of another example of an article of footwear according to the principles of the present disclosure, where the article of footwear is in a relaxed state;

FIG. 5B is a perspective view of the article of footwear of FIG. 5A, where the article of footwear is in a contracted state;

FIG. 6A is a cross-sectional view of the article of footwear of FIG. 5A, taken along Line 6A-6A in FIG. 5A;

FIG. 6B is a cross-sectional view of the article of footwear of FIG. 5B, taken along Line 6B-6B in FIG. 5B;

FIG. 7A is a front perspective view of another article of footwear according to the present disclosure, where the article of footwear is in a relaxed state;

FIG. 7B is a front perspective view of the article of footwear of FIG. 7A, where the article of footwear is in a constricted state;

FIG. 8A is a cross-sectional view of the article of footwear of FIG. 7A, taken along Line 8A-8A in FIG. 7A;

FIG. 8B is a cross-sectional view of the article of footwear of FIG. 7B, taken along Line 8B-8B in FIG. 7B;

FIG. 9A is a front perspective view of another article of footwear according to the present disclosure, where the article of footwear is in a relaxed state;

FIG. 9B is a front perspective view of the article of footwear of FIG. 9A, where the article of footwear is in a constricted state;

FIG. 10A is a cross-sectional view of the article of footwear of FIG. 9A, taken along Line 10A-10A in FIG. 9A;

FIG. 10B is a cross-sectional view of the article of footwear of FIG. 9B, taken along Line 10B-10B in FIG. 9B;

FIGS. 11A-11E show example swatches of lattice structures and materials for compressible components according to the present disclosure; and

FIG. 12A-12C show steps and components for forming an example compressible component according to the present disclosure.

Corresponding reference numerals indicate corresponding parts throughout the drawings.

DETAILED DESCRIPTION

Example configurations will now be described more fully with reference to the accompanying drawings. Example configurations are provided so that this disclosure will be

thorough, and will fully convey the scope of the disclosure to those of ordinary skill in the art. Specific details are set forth such as examples of specific components, devices, and methods, to provide a thorough understanding of configurations of the present disclosure. It will be apparent to those of ordinary skill in the art that specific details need not be employed, that example configurations may be embodied in many different forms, and that the specific details and the example configurations should not be construed to limit the scope of the disclosure.

The terminology used herein is for the purpose of describing particular exemplary configurations only and is not intended to be limiting. As used herein, the singular articles "a," "an," and "the" may be intended to include the plural forms as well, unless the context clearly indicates otherwise.

The terms "comprises," "comprising," "including," and "having," are inclusive and therefore specify the presence of features, steps, operations, elements, and/or components, but do not preclude the presence or addition of one or more other features, steps, operations, elements, components, and/or groups thereof. The method steps, processes, and operations described herein are not to be construed as necessarily requiring their performance in the particular order discussed

or illustrated, unless specifically identified as an order of performance. Additional or alternative steps may be employed.

When an element or layer is referred to as being "on," "engaged to," "connected to," "attached to," or "coupled to" another element or layer, it may be directly on, engaged, connected, attached, or coupled to the other element or layer, or intervening elements or layers may be present. In contrast, when an element is referred to as being "directly on," "directly engaged to," "directly connected to," "directly attached to," or "directly coupled to" another element or layer, there may be no intervening elements or layers present. Other words used to describe the relationship between elements should be interpreted in a like fashion (e.g., "between" versus "directly between," "adjacent" versus "directly adjacent," etc.). As used herein, the term "and/or" includes any and all combinations of one or more of the associated listed items.

The terms first, second, third, etc. may be used herein to describe various elements, components, regions, layers and/or sections. These elements, components, regions, layers and/or sections should not be limited by these terms. These terms may be only used to distinguish one element, component, region, layer or section from another region, layer or section. Terms such as "first," "second," and other numerical terms do not imply a sequence or order unless clearly indicated by the context. Thus, a first element, component, region, layer or section discussed below could be termed a second element, component, region, layer or section without departing from the teachings of the example configurations.

An adjustment element for an article of footwear includes a bladder having a barrier layer defining an interior void and a compressible component disposed within the interior void and including a lattice structure defining a plurality of reliefs formed in the lattice structure, the compressible component operable between an expanded state when the interior void includes a first pressure and a contracted state when the interior void includes a second pressure.

The adjustment element may include one or more of the following optional features. For example, the reliefs may be parallelogram-shaped and may extend through a thickness of the compressible component. Additionally or alternatively, the lattice structure may define a first adjustment zone including a first plurality of reliefs oriented in a first direction and a second adjustment zone including a plurality of reliefs oriented in a second direction different from the first direction.

In one configuration, the compressible component may include a resilient polymeric material. The resilient polymeric material may be a foam material.

A port may be connected to the barrier layer and may provide fluid communication between the interior void and a variable pressure source. Additionally or alternatively, the first pressure may be equal to or greater than ambient pressure and the second pressure may be less than ambient pressure.

The adjustment element may include an interior seam separating the bladder into a first chamber and a second chamber. Further, the adjustment element may form an upper of an article of footwear.

In one configuration, the compressible component may include a first plurality of the reliefs operable to contract in a first direction in a forefoot region of the upper and a second plurality of the reliefs operable to contract in a second direction in a mid-foot region of the upper.

In another configuration, an article of footwear includes a bootie defining an interior void and an adjustment element

attached to the bootie and including a bladder having a barrier layer defining an interior void and a compressible component disposed within the interior void, the compressible component including a lattice structure defining a plurality of reliefs formed in the lattice structure, the compressible component operable between an expanded state when the interior void includes a first pressure and a contracted state when the interior void includes a second pressure.

10 The article of footwear may include one or more of the following optional features. For example, the reliefs may be parallelogram-shaped and extend through a thickness of the compressible component. Additionally or alternatively, the lattice structure may define a first adjustment zone including 15 a first plurality of the reliefs oriented in a first direction and a second adjustment zone including a second plurality of the reliefs oriented in a second direction different from the first direction. The first plurality of the reliefs may be operable to contract in a first direction in a forefoot region and the second plurality of the reliefs may be operable to contract in a second direction in a mid-foot region.

In one configuration, the compressible component may include a resilient polymeric material. The resilient polymeric material may be a foam material.

25 A port may be connected to the barrier layer and may provide fluid communication between the interior void and a variable pressure source. Additionally or alternatively, the first pressure may be equal to or greater than ambient pressure and the second pressure may be less than ambient pressure.

30 The adjustment element may include an interior seam separating the bladder into a first chamber and a second chamber. Further, the bootie may be exposed along a throat region of the article of footwear.

35 The details of one or more implementations of the disclosure are set forth in the accompanying drawings and the description below. Other aspects, features, and advantages will be apparent from the description and drawings, and from the claims.

40 Referring to FIGS. 1-4, an article of footwear 10 includes an upper 100 and a sole structure 200 attached to the upper 100. The footwear 10 may further include an anterior end 12 associated with a forward-most point of the footwear, and a posterior end 14 corresponding to a rearward-most point of the footwear 10. A longitudinal axis A₁₀ of the footwear 10 extends along a length of the footwear 10 from the anterior end 12 to the posterior end 14 parallel to a ground surface, and generally divides the footwear 10 into a medial side 16 and a lateral side 18. Accordingly, the medial side 16 and the lateral side 18 respectively correspond with opposite sides of the footwear 10 and extend from the anterior end 12 to the posterior end 14. As used herein, a longitudinal direction refers to the direction extending from the anterior end 12 to the posterior end 14, while a lateral direction refers to the 55 direction transverse to the longitudinal direction and extending from the medial side 16 to the lateral side 18.

The article of footwear 10 may be divided into one or more regions. The regions may include a forefoot region 20, a mid-foot region 22, and a heel region 24. The forefoot region 20 is associated with phalanges and metatarsal bones of a foot. The mid-foot region 22 may correspond with an arch area of the foot, and the heel region 24 may correspond with rear portions of the foot, including a calcaneus bone.

60 The upper 100 defines an interior void 102 and an ankle opening 104, which cooperate to receive and secure a foot for support on the sole structure 200. The upper 100, and components thereof, may be described as including various

subcomponents or regions. For example, the upper 100 includes a toe cap 106 disposed at the anterior end 12 and extending over the toes from the medial side 16 to the lateral side 18. A pair of quarter panels 108 extend from the toe cap 106 in the mid-foot region 22 on opposite sides of the interior void 102. A throat 110 extends across the top of the upper 100 and defines an instep region extending between the quarter panels 108 from the toe cap 106 to the ankle opening 104. In the illustrated example, the throat 110 is enclosed, whereby a material panel extends between the opposing quarter panels 108 in the instep region to cover the interior void 102. Here, the material panel covering the throat 110 may be formed of a material having a higher modulus of elasticity than the material forming the quarter panels 108.

The upper 100 of the article of footwear 10 may be further described as including heel side panels 112 extending through the heel region 24 along the medial and lateral sides 16, 18 of the ankle opening 104. A heel counter 114 wraps around the posterior end 14 of the footwear 10 and connects the heel side panels 112. Uppermost edges of the throat 110, the heel side panels 112, and the heel counter 114 cooperate to form a collar 116, which defines the ankle opening 104 of the interior void 102.

In the example of FIGS. 1A-4B, the upper 100 includes an inner bootie 120 defining the interior void 102. The bootie 120 may be formed from one or more materials that are stitched or adhesively bonded together to define the interior void 102. Suitable materials of the upper bootie may include, but are not limited to, textiles, foam, leather, and synthetic leather. The example bootie 120 may be formed as an inner liner including a combination of one or more substantially inelastic or non-stretchable materials and one or more substantially elastic or stretchable materials disposed in different regions of the bootie 120 to facilitate movement of the article of footwear 10 between the tightened state and the loosened state. The one or more elastic materials may include any combination of one or more elastic fabrics such as, without limitation, spandex, elastane, rubber or neoprene. The one or more inelastic materials may include any combination of one or more of thermoplastic polyurethanes, nylon, leather, vinyl, or another material/fabric that does not impart properties of elasticity.

The upper 100 further includes an integrated adjustment element 130 attached to the bootie 120. The adjustment element 130 includes a bladder 132 forming an interior void 134 having a compressible component 136 disposed therein. As shown in FIGS. 12A-12C, the compressible component 136 includes a first surface 138a on a first side of the compressible component and a second surface 138b on an opposite second side of the compressible component. A distance from the first surface 138a to the second surface 138b defines a thickness of the compressible component 136. As discussed in greater detail below, the compressible component 136 is operable to transition the adjustable element 130 and the upper 100 between a relaxed state (FIGS. 1A and 2A) and a constricted state (FIGS. 1B and 2B).

In the illustrated example, the adjustment element 130 includes a toe portion including or defining toe cap 106 of the upper 100 and a pair of side portions extending along the medial and lateral sides 16, 18 on opposite sides of the throat 110 from the toe cap 106 to the heel region 24. As shown, each of the side portions include or define a respective quarter panel 108 and heel side panel 112 of the upper 100 on one of the medial side 16 and the lateral side 18. Thus, the throat 110 of the upper 100 is defined by the material of

the bootie 120 and does not include the adjustment element 130. As shown in FIG. 3, the side portions of the adjustment element 130 each terminate along the respective medial and lateral sides 16, 18 of the heel counter 114 such that the bootie 120 is exposed and unrestrained along the posterior end 14. Accordingly, the ankle opening 104, the throat 110, and the heel counter 114 are defined only by an elastic material of the bootie 120 and may stretch to a greater extent than portions 106, 108, 112 of the upper 100 including the adjustment element 130, thereby allowing the upper 100 to stretch around to foot to be easily donned and doffed.

In the illustrated example, the adjustment element 130 includes an inner barrier layer 140a attached to an exterior surface of the bootie 120, and an outer barrier layer 140b defining at least a portion of an exterior surface of the upper 100. Interior surfaces of the barrier layers 140a, 140b face each other and are joined to each other at discrete locations to form a peripheral seam 142 that surrounds the interior void 134 to define a chamber 144 of the bladder 132.

As used herein, the term "barrier layer" (e.g., barrier layers 140a, 140b) encompasses both monolayer and multilayer films. In some embodiments, one or both of barrier layers the 140a, 140b are each produced (e.g., thermoformed or blow molded) from a monolayer film (a single layer). In other embodiments, one or both of the barrier layers 140a, 140b are each produced (e.g., thermoformed or blow molded) from a multilayer film (multiple sublayers). In either aspect, each layer or sublayer can have a film thickness ranging from about 0.2 micrometers to about 1 millimeter. In further embodiments, the film thickness for each layer or sublayer can range from about 0.5 micrometers to about 500 micrometers. In yet further embodiments, the film thickness for each layer or sublayer can range from about 1 micrometer to about 100 micrometers.

One or both of the barrier layers 140a, 140b can independently be transparent, translucent, and/or opaque. As used herein, the term "transparent" for a barrier layer and/or a chamber means that light passes through the barrier layer in substantially straight lines and a viewer can see through the barrier layer. In comparison, for an opaque barrier layer, light does not pass through the barrier layer and one cannot see clearly through the barrier layer at all. A translucent barrier layer falls between a transparent barrier layer and an opaque barrier layer, in that light passes through a translucent layer but some of the light is scattered so that a viewer cannot see clearly through the layer.

The barrier layers 140a, 140b can each be produced from an elastomeric material that includes one or more thermoplastic polymers and/or one or more cross-linkable polymers. In an aspect, the elastomeric material can include one or more thermoplastic elastomeric materials, such as one or more thermoplastic polyurethane (TPU) copolymers, one or more ethylene-vinyl alcohol (EVOH) copolymers, and the like.

As used herein, "polyurethane" refers to a copolymer (including oligomers) that contains a urethane group (—N(C=O)O—). These polyurethanes can contain additional groups such as ester, ether, urea, allophanate, biuret, carbodiimide, oxazolidinyl, isocynaurate, uretdione, carbonate, and the like, in addition to urethane groups. In an aspect, one or more of the polyurethanes can be produced by polymerizing one or more isocyanates with one or more polyols to produce copolymer chains having (—N(C=O)O—) linkages.

Examples of suitable isocyanates for producing the polyurethane copolymer chains include diisocyanates, such as aromatic diisocyanates, aliphatic diisocyanates, and combi-

nations thereof. Examples of suitable aromatic diisocyanates include toluene diisocyanate (TDI), TDI adducts with trimethoxypropene (TMP), methylene diphenyl diisocyanate (MDI), xylene diisocyanate (XDI), tetramethylxylylene diisocyanate (TMXDI), hydrogenated xylene diisocyanate (HXDI), naphthalene 1,5-diisocyanate (NDI), 1,5-tetrahydrophthalene diisocyanate, para-phenylene diisocyanate (PPDI), 3,3'-dimethyldiphenyl-4,4'-diisocyanate (DDDI), 4,4'-dibenzyl diisocyanate (DBDI), 4-chloro-1,3-phenylene diisocyanate, and combinations thereof. In some embodiments, the copolymer chains are substantially free of aromatic groups.

In particular aspects, the polyurethane polymer chains are produced from diisocyanates including HDI, TDI, MDI, H12 aliphatics, and combinations thereof. In an aspect, the thermoplastic TPU can include polyester-based TPU, polyether-based TPU, polycaprolactone-based TPU, polycarbonate-based TPU, polysiloxane-based TPU, or combinations thereof.

In another aspect, the polymeric layer can be formed of one or more of the following: EVOH copolymers, poly(vinyl chloride), polyvinylidene polymers and copolymers (e.g., polyvinylidene chloride), polyamides (e.g., amorphous polyamides), amide-based copolymers, acrylonitrile polymers (e.g., acrylonitrile-methyl acrylate copolymers), polyethylene terephthalate, polyether imides, polyacrylic imides, and other polymeric materials known to have relatively low gas transmission rates. Blends of these materials as well as with the TPU copolymers described herein and optionally including combinations of polyimides and crystalline polymers, are also suitable.

The barrier layers 140a, 140b may include two or more sublayers (multilayer film) such as shown in Mitchell et al., U.S. Pat. No. 5,713,141 and Mitchell et al., U.S. Pat. No. 5,952,065, the disclosures of which are incorporated by reference in their entirety. In embodiments where the barrier layers 140a, 140b include two or more sublayers, examples of suitable multilayer films include microlayer films, such as those disclosed in Bonk et al., U.S. Pat. No. 6,582,786, which is incorporated by reference in its entirety. In further embodiments, barrier layers 140a, 140b may each independently include alternating sublayers of one or more TPU copolymer materials and one or more EVOH copolymer materials, where the total number of sublayers in each of the barrier layers 140a, 140b includes at least four (4) sublayers, at least ten (10) sublayers, at least twenty (20) sublayers, at least forty (40) sublayers, and/or at least sixty (60) sublayers.

The chamber 144 can be produced from the barrier layers 140a, 140b using any suitable technique, such as thermo-forming (e.g. vacuum thermoforming), blow molding, extrusion, injection molding, vacuum molding, rotary molding, transfer molding, pressure forming, heat sealing, casting, low-pressure casting, spin casting, reaction injection molding, radio frequency (RF) welding, and the like. In an aspect, the barrier layers 140a, 140b can be produced by co-extrusion followed by vacuum thermoforming to produce an inflatable chamber 144, which can optionally include one or more valves (e.g., one way valves) that allows the chamber 144 to be filled with the fluid (e.g., gas).

The chamber 144 can be provided in a fluid-filled (e.g., as provided in footwear 10) or in an unfilled state. The chamber 144 can be filled to include any suitable fluid, such as a gas or liquid. In an aspect, the gas can include air, nitrogen (N₂), or any other suitable gas. In other aspects, the chamber 144 can alternatively include other media, such as pellets, beads, ground recycled material, and the like (e.g., foamed beads

and/or rubber beads). The fluid provided to the chamber 144 can result in the chamber 144 being pressurized. Alternatively, the fluid provided to the chamber 144 can be at atmospheric pressure such that the chamber 144 is not pressurized but, rather, simply contains a volume of fluid at atmospheric pressure.

The chamber 144 desirably has a low gas transmission rate to preserve its retained gas pressure. In some embodiments, the chamber 144 has a gas transmission rate for nitrogen gas that is at least about ten (10) times lower than a nitrogen gas transmission rate for a butyl rubber layer of substantially the same dimensions. In an aspect, chamber 144 has a nitrogen gas transmission rate of 15 cubic-centimeter/square-meter-atmosphere-day (cm³/m²·atm·day) or less for an average film thickness of 500 micrometers (based on thicknesses of the barrier layers 140a, 140b). In further aspects, the transmission rate is 10 cm³/m²·atm·day or less, 5 cm³/m²·atm·day or less, or 1 cm³/m²·atm·day or less.

In some implementations, the inner barrier layer 140a and the outer barrier layer 140b cooperate to define a geometry (e.g., thicknesses, width, and lengths) of the chamber 144. The peripheral seam 142 may extend around the chamber 144 to seal the fluid (e.g., air) within the chamber 144. Thus, the chamber 144 is associated with an area of the bladder 132 where interior surfaces of the upper and lower barrier layers 140a, 140b are not joined together and, thus, are separated from one another.

In some examples, the barrier layers 140a, 140b may include the same materials to provide the chamber 144 with a homogenous barrier construction, such that both sides of the adjustment element 130 will contract and relax at the same rate when pressure within the chamber 144 is adjusted. Alternatively, a first one of the barrier layers 140a, 140b may be at least partially constructed of a different barrier material and/or configuration than the other one of the barrier layers 140a, 140b to selectively impart a contour as the adjustment element 130 transitions between the relaxed state and the contracted state. For example, one of the barrier layers 140a, 140b may be at least partially formed with a different modulus of elasticity and/or stiffness than the other barrier layer 140a, 140b, such that when the adjustment element 130 transitions from the relaxed state to the contracted state, the first one of the barrier layers 140a, 140b contracts at a different rate than the other barrier layer 140a, 140b to cause the adjustment element to curl.

The compressible component 136 is disposed within the interior void 134 of the adjustment element 130 and forms a transformable structure operable to transition the upper 100 between the relaxed state and the constricted state. The first surface 138a of the compressible component 136 faces the inner barrier layer 140a and the second surface 138b faces the outer barrier layer 140b. In this example, the compressible component 136 includes a collapsible lattice structure 146 having a plurality of apertures or reliefs 148 formed through the thickness (i.e., direction from the inner barrier layer 140a to the outer barrier layer 140b) of the compressible component 136. Generally, when a pressure within the chamber 144 is reduced, the lattice structure 146 is configured to collapse within the chamber 144 to transition the adjustment element 130 and the upper 100 from the relaxed or expanded state to the constricted state.

One or both surfaces 138a, 138b of the compressible component 136 may be attached to the corresponding barrier layer 140a, 140b when the adjustment element 130 is assembled. In one configuration, one or both of the first surface 138a and the second surface 138b may be fully

attached to the corresponding one of the barrier layers 140a, 140b. Thus, as the compressible component 136 moves between the relaxed state and the contracted state, the surfaces 138a, 138b of the compressible component 136 directly pull the barrier layers 140a, 140b to transition the barrier layers 140a, 140b between the relaxed state and the contracted state.

In other examples, one or both of the surfaces 138a, 138b of the compressible component 136 may be fully detached from the barrier layers 140a, 140b. In this configuration, the barrier layers 140a, 140b are free to slide with respect to the surfaces 138a, 138b of the compressible component 136 as the compressible component 136 transitions between the relaxed state and the contracted state. Here, the barrier layers 140a, 140b may be indirectly influenced into the relaxed and contracted states by the compressible component 136.

In other implementations, at least one of the surfaces 138a, 138b of the compressible component 136 may be partially attached to the barrier layers 140a, 140b. For example, the compressible component 136 may be attached to the barrier layers 140a, 140b along a periphery of the surface 138a, 138b such that the interior region of the respective surface 138a, 138b is detached or independent from the barrier layers 140a, 140b. Thus, as the compressible component 136 transitions between the relaxed state and the contracted state, the barrier layers 140a, 140b are influenced into the relaxed state and the contracted state by the outer periphery of the compressible component 136. Alternatively, at least one of the surfaces 138a, 138b of the compressible component 136 may be zonally attached to a respective one of the barrier layers 140a, 140b. For instance, one or both of the surfaces 138a, 138b may be attached to the respective barrier layer 140a, 140b at one of the adjustment zones 150a-150c and detached from the barrier layer 140a, 140b at another one of the adjustment zones 150a-150c.

With continued reference to FIGS. 1A and 1B, the reliefs 148 of the compressible component 136 may be formed as polygonal-shaped apertures extending through the thickness of the compressible component 136. For instance, the reliefs 148 may be rectangular or parallelogram-shaped reliefs 148 including a length L₁₄₈ extending across a first pair of opposing corners and a width W₁₄₈ extending across a second pair of opposing corners that are arranged transverse (e.g., perpendicular) to the length L₁₄₈. In the illustrated example, the width W₁₄₈ of each relief 148 is less than the length L₁₄₈ such that the reliefs 148 are configured to collapse along the widthwise direction when the pressure is reduced within the chamber 144. Accordingly, orientations of the reliefs 148 may be selected depending on a desired transition between the expanded state and the constricted state.

In the illustrated example, the reliefs 148 of the compressible component 136 are arranged in a plurality of adjustment zones 150a, 150b, 150c to impart different transformation characteristics along the upper 100. For example, the compressible component 136 includes a first adjustment zone 150a arranged along the toe cap 106 of the upper 100 and including an array (e.g., rows and columns) of the reliefs 148 having widths W₁₄₈ oriented along a longitudinal direction (i.e., from an anterior end 12 to the posterior end 14) of the upper 100 and lengths L₁₄₈ oriented across (i.e., transverse to the longitudinal axis A₁₀) the upper 100. Thus, the reliefs 148 of the first adjustment zone 150a are configured to selectively contract the toe cap 106 of upper 100 along the lengthwise direction over the toes.

The side portions of the compressible component 136 define a second adjustment zone 150b extending along the quarter panels 108 on each of the medial side 16 and the lateral side 18 in the mid-foot region 22. The second adjustment zone 150b includes an array of the reliefs 148 with widths W₁₄₈ oriented transverse or perpendicular to the longitudinal direction of the upper 100. Accordingly, the second adjustment zone 150b is configured to contract the upper 100 across the mid-foot region 22 of the on each of the medial side 16 and the lateral side 18. As discussed above, the throat 110 of the upper 100 is formed by an elastic material of the bootie 120. Thus, when the second adjustment zone 150b moves from the relaxed state to the constricted state, the throat 110 may be drawn upon and stretch around the dorsal surface (i.e., the instep) of the foot.

With continued reference to FIGS. 1A and 1B, the compressible component 136 includes a third adjustment zone 150c formed along the heel side panels 112 on each of the medial side 16 and the lateral side 18. The third adjustment zone 150c extends at least partially around a heel region of the upper 100 from a medial side to a lateral side. Here, the reliefs 148 are oriented with the widths W₁₄₈ aligned substantially parallel with the sole structure 200 and the lengths L₁₄₈ oriented along a direction from the sole structure 200 to the ankle opening 104. Accordingly, the third adjustment zone 150c is configured to constrict the upper 100 around the heel of the foot. The posterior end 14 of the heel counter 114 includes an elastic material of the bootie 120 and is configured to stretch around the heel as the adjustment element 130 is moved from the relaxed state to the constricted state.

The compressible component 136 includes one or more resilient materials configured to bias the adjustment element 130 and the upper 100 towards expanded or relaxed state. For example, the compressible component 136 may include an elastomeric material, such as an ethylene-vinyl acetate foam. In other examples, the compressible component 136 may include unfoamed polymers, such as thermoplastic polyurethane. Optionally, the compressible component may include fiber-reinforced elastomeric materials. In addition to including different materials, the lattice structure 146 may include different geometrical configurations to impart different constriction profiles in different areas of the upper 100. Examples of different geometries are discussed below with respect to FIGS. 11A-11E. Optionally, a thickness of the compressible component 136 ranges from 4 mm to 6 mm to provide the upper 100 with a relatively low profile while also providing sufficient structural strength for biasing the upper 100 to the expanded or relaxed state.

In use, the upper 100 is moved between the relaxed state and the constricted state by adjusting a fluid pressure within the interior void 134. For example, the pressure within the interior void 134 may be reduced by drawing a vacuum within the interior void 134 through a port 126 attached to the bladder 132. The vacuum may be drawn using a pressure source, such as a pump 160 integrated within the footwear 10 or provided as a peripheral (i.e., independent) accessory to the footwear 10. For illustrative purposes, the pump 160 of the present example is shown disposed in the heel region 24 of the sole structure 200. However, the pump 160 may be attached or disposed in any portion of the article of footwear 10, such as on the upper 100 or in other regions of the sole structure 200. Further, the pump 160 may be a peripheral accessory not attached to the shoe, such as a hand pump. As the pressure is reduced (e.g., below ambient) within the interior void 134, the lattice structure 146 collapses along the width-wise directions of the reliefs 148 and the upper 100 constricts around the foot. Conversely, to move the

11

upper **100** to the relaxed state, the pressure within the interior void **134** is increased and the resilient material and/or geometry of the lattice structure **146** biases the upper **100** towards the expanded state.

With particular reference to FIGS. 5A-6B, another example of a configuration of an article of footwear **10a** having an integrated adjustment element **130a** is shown. In view of the substantial similarity in structure and function of the components associated with the article of footwear **10** with respect to the article of footwear **10a**, like reference numerals are used hereinafter and in the drawings to identify like components while like reference numerals containing letter extensions are used to identify those components that have been modified.

The article of footwear **10a** shown in FIGS. 5A-6B includes an upper **100a** and a sole structure **200** attached to the upper **100a**. The upper **100a** includes the bootie **120** and an adjustment element **130a** attached to the bootie **120**. Unlike the previous example of FIGS. 1A-3 where the bootie **120** is exposed along the throat **110**, the adjustment element **130a** of the upper **100a** of the present example extends over the throat **110** from the medial quarter panel **108** to the lateral quarter panel **108**. Thus, the adjustment element **130a** is configured to selectively constrict the upper **100a** along the dorsal surface of the foot. The adjustment element **130a** includes a bladder **132a** forming an interior void **134a** having a compressible component **136a** disposed therein. As discussed in greater detail below, the compressible component **136a** is operable to transition the adjustable element **130a** and the upper **100a** between a relaxed state (FIG. 5A) and a constricted state (FIG. 5B).

In the illustrated example, the adjustment element **130a** includes the inner barrier layer **140a** and the outer barrier layer **140b** defining at least a portion of an exterior surface of the upper **100a**. Interior surfaces of the barrier layers **140a**, **140b** face each other and are joined to each other at discrete locations to form one or more seams **142a**, **142b** that separate the interior void **134a** of the bladder **132a** into one or more chambers **144a**, **144b**. In the illustrated example, the adjustment element **130a** includes peripheral seams **142a** sealing the interior void **134a** and an interior seam **142b** defining a flexure that separates the interior void **134a** into an anterior chamber **144a** and a posterior chamber **144b**. Thus, the interior seam **142b** allows the upper **100a** and the adjustment element **130a** to articulate along the metatarsophalangeal (MTP) joint of the foot. Optionally, the seams **142a**, **142b** may include perforations **122** or a breathable material to allow air transfer between the interior void **102** of the upper **100a** and the exterior of the upper **100a**.

The compressible component **136a** is disposed within the interior void **134a** of the adjustment element **130a** and forms a transformable structure operable to transition the upper **100a** between the relaxed state and the constricted state. In this example, the compressible component **136a** includes a collapsible lattice structure **146** having a plurality of the apertures or reliefs **148** formed through a thickness (i.e., direction from the inner barrier layer **140a** to the outer barrier layer **140b**) of the compressible component **136a**. Generally, when a pressure within the chambers **144a**, **144b** is reduced, the lattice structure **146** is configured to collapse within chambers **144a**, **144b** to transition the adjustment element **130a** and the upper **100a** from the relaxed state to the constricted state. Optionally, the compressible component **136a** may be attached to the interior surface of one or both of the barrier layers **140a**, **140b**.

In the illustrated example, the reliefs **148** of the compressible component **136a** are arranged in a plurality of

12

adjustment zones **150a**, **150d**, **150e**, **150e** to impart different transformation characteristics along the upper **100a**. For example, the anterior chamber **144a** includes the first adjustment zone **150a** and a second adjustment zone **150d**. The second adjustment zone **150d** has a second array of the reliefs **148** extending between the first adjustment zone **150a** and the interior seam **142b** with widths **W₁₄₈** oriented transverse or perpendicular to the longitudinal direction of the upper **100a**. Accordingly, the second adjustment zone **150d** is configured to constrict the upper **100a** across a ball region of the foot from the medial side **16** to the lateral side **18** of the upper **100a**.

With continued reference to FIGS. 5A and 5B, the compressible component **136a** includes a third adjustment zone **150e** and a fourth adjustment zone **150f** disposed in the posterior chamber **144b**. The third adjustment zone **150e** is disposed along a mid-foot region of the upper **100a** and includes an array of the reliefs **148** having widths **W₁₄₈** oriented transverse to the longitudinal direction of the upper **100a**, similar to the reliefs **148** of the second adjustment zone **150d**. Accordingly, the third adjustment zone **150e** is configured to constrict the upper **100a** across the mid-foot region of the foot from the medial side **16** to the lateral side **18**. The fourth adjustment zone **150f** extends continuously around the heel counter **114** of the upper **100a** from the medial side **16** to a lateral side **18**. Here, the reliefs **148** are oriented with the widths **W₁₄₈** aligned substantially parallel with the sole structure **200** and the lengths **L₁₄₈** oriented along a direction from the sole structure **200** to the ankle opening **104**. Accordingly, the fourth adjustment zone **150f** is configured to constrict the upper **100a** around the heel of the foot.

FIGS. 6A and 6B illustrate a cross-sectional view of an example of the upper **100a** transitioning from the relaxed state (FIG. 6A) to the constricted state (FIG. 6B). In FIG. 6A, the adjustment element **130a** is in the relaxed state. As shown, the lattice structure **146** within the adjustment element **130a** is expanded such that the reliefs **148** of the lattice structure **146** define a first width **W₁₄₈**. To move the adjustment element **130a** to the constricted state, pressure within the interior void **134a** of the adjustment element **130a** is reduced until a vacuum force overcomes the opposing biasing force imparted by the resilient material of the compressible component **136a** collapses the lattice structure **146** at the reliefs **148**, transitioning the reliefs from the expanded width **W₁₄₈** to a collapsed width **W₁₄₈**. As the adjustment element **130a** collapses, the outer barrier layer **140b** may be drawn into the reliefs **148** towards the inner barrier layer **140a**. Optionally, the outer barrier layer **140b** may contact the inner barrier layer **140a** such that friction between the inner barrier layer **140a** and the outer barrier layer **140b** causes the upper **100a** to increase in stiffness when the adjustment element **130a** is in the constricted state. While FIGS. 6A and 6B provide an example of the adjustment element **130a** across the third adjustment zone **150e**, the adjustment zones **150a**-**150c** of the article of footwear **10** and the adjustment zones **150d**, **150f** of the upper **100a** function in a similar fashion.

With particular reference to FIGS. 7A-8B, another example of a configuration of an article of footwear **10b** having an integrated adjustment element **130b** is shown. In view of the substantial similarity in structure and function of the components associated with the article of footwear **10** with respect to the article of footwear **10b**, like reference numerals are used hereinafter and in the drawings to identify

like components while like reference numerals containing letter extensions are used to identify those components that have been modified.

The example of the article of footwear 10b shown in FIGS. 7A and 7B includes a high-top style upper 100b including a cuff 118 configured to extend around an ankle of a wearer between the heel counter 114 and the collar 116. As shown, a bootie 120 (best seen in FIGS. 8A-8B) of the upper 100b includes a closure 124 extending along the throat 110 to move the upper 100b between an open configuration and a closed configuration. In this example, the closure 124 includes a zipper 124 extending along a length of the throat 110 from the toe cap 106 to the collar 116. The closure 124 may include other mechanisms for moving the upper 100b between the open state and the closed state, such as buttons, straps, hooks, laces, etc. Optionally, as explained in further detail below, the adjustment element 130b may include a port 126 in fluid communication with an interior void 134b of a bladder 132b (both best seen in FIG. 8A). The port 126 can be selectively coupled to a pressure source, such as a pump, to increase or decrease pressure within the bladder 132b.

For example, the upper 100b may include an adjustment element 130b including a bladder 132b having an interior void 134b and a compressible component 136b disposed within the interior void 134b. In this example, the adjustment element 130b extends along the entire upper 100b except for the closure 124 and an optional interior seam 142c extending along the longitudinal axis A₁₀ and connecting anterior end 12 to the closure 124. As shown, the adjustment element 130b includes a single chamber 144c having a unitary lattice structure 146 and reliefs 148 extending along the toe cap 106, quarter panels 108, heel side panels 112, the heel counter 114, and the cuff 118. While the illustrated example of the compressible component 136b includes a homogenous lattice structure 146, the compressible component 136b may have a variable lattice structure 146 tuned to constrict in different directions or amounts around the foot, as discussed below with respect to FIGS. 11A-11E and as shown in the previous arrangements discussed above. Thus a first portion of the compressible component 136b may include a first material and/or lattice configuration and a second portion of the compressible component 136b may include a second material and/or lattice configuration.

With particular reference to FIGS. 9A-10B, another example of a configuration of an article of footwear 10c having an integrated adjustment element 130c is shown. In view of the substantial similarity in structure and function of the components associated with the article of footwear 10 with respect to the article of footwear 10c, like reference numerals are used hereinafter and in the drawings to identify like components while like reference numerals containing letter extensions are used to identify those components that have been modified.

The article of footwear 10c includes an upper 100c similar to the upper 100b previously described. Thus, the upper 100c includes an adjustment element 130c having a bladder 132c and a compressible component 136c. The bladder 132c includes a peripheral seam 142d and a chamber 144d. In this example, the upper 100c includes a closure 124 extending along the heel side panel 112 from the sole structure 200 to the collar 116 on one of the medial side 16 or lateral side 18 of the ankle opening 104. The closure 124 may be moved between an open configuration (FIG. 9A) and a closed configuration (FIG. 9B) to selectively increase the size of the ankle opening 104, thereby easing donning and doffing of the article of footwear 10c.

In the present example, the adjustment element 130c extends over the throat 110 of the upper 100c. The compressible component 136c is disposed within an interior void 134c of the bladder 132c and includes a homogenous lattice structure 146. However, the lattice structure 146 and reliefs 148 may be variable and include different properties in different zones or regions of the upper 100c. Generally, when a pressure within the chamber 144d is reduced, the lattice structure 146 is configured to collapse within chamber 144 to transition the adjustment element 130c and the upper 100c from the relaxed state (FIG. 10A) to the constricted state (FIG. 10B), as discussed previously. Optionally, the compressible component 136c may be attached to the interior surface of one or both of the barrier layers 140a, 140b.

FIGS. 11A-11E illustrate swatches 1000a-1000e having different examples of materials and configurations for lattice structures 146 and reliefs 148. As discussed above, the compressible components 136-136c may include homogenous lattice structures 146 or may include variable lattice structures 146 including any combination of the materials or configurations shown in the swatches 1000a-1000e of FIGS. 11A-11E.

FIG. 11A shows a lattice structure swatch 1000a including a non-foamed polymer material. Optionally, the polymer material may include fiber reinforcement (e.g., glass fibers). The lattice structure swatch 1000a may be described as including a staggered array of parallelogram-shaped reliefs including first reliefs 148a having first lengths L_{148a} and widths W_{148a} and second reliefs 148b having second lengths L_{148b} and widths W_{148b} that are less than the first reliefs 148a. As shown, the first reliefs 148a are arranged corner-to-corner with each other in first rows 1002a and first columns 1004a and the second reliefs 148b are arranged corner-to-corner with each other in second rows 1006a and second columns 1008a. The first rows 1002a and second rows 1006a are alternatingly arranged such that each consecutive one the second reliefs 148b in each second row 1006a is received between a consecutive pair of the first reliefs 148a, and vice versa. The alternating arrangement of the reliefs 148a, 148b provides a combination of increased range of motion among the larger first reliefs 148a and stiffness among the smaller second reliefs 148b. Sizes and thicknesses of the lattice may be selected to tune performance of the structure.

FIG. 11B shows another lattice structure swatch 1000b including a non-foamed polymer material. Here, the lattice structure swatch 1000b may be described as including a diagonal rectangular array configuration including a homogenous arrangement of rectangular reliefs 148c arranged in diagonal rows 1002b and columns 1004b to form a grid pattern. As may be seen, the lengths L_{148c} of the reliefs 148c are substantially the same as the dimension of the widths W_{148c} of the reliefs 148c. As with the lattice structure swatch 1000a, thicknesses of the lattice and/or dimensions of the reliefs 148b may be modified to change properties of the lattice structure.

FIGS. 11C and 11D show examples of lattice structure swatches 1000c, 1000d including foamed elastomeric materials. The foamed elastomeric materials may include closed-cell or open-cell foams configured to collapse under pressure. Thus, in addition to the collapsible lattice structure defined by the reliefs 148, the material of the lattice structure may also collapse, allowing a thickness of a compressible component to compress between barrier layers 140a, 140b of an adjustment element. The lattice structure swatch 1000c has a staggered parallelogram shape similar to the lattice

15

structure swatch **1000a** and the lattice structure swatch **1000d** has a rectangular array configuration similar to the lattice structure swatch **1000b**.

In another example, FIG. 11E shows an example of a lattice structure swatch **1000e** including a tapered rectangular array. Here, lattice structure swatch **1000e** includes a plurality substantially rectangular reliefs **148e** arranged in rows **1002e** and columns **1004e**. Each relief **148e** includes a length L_{148e} measured along the rows **1002e** and a width W_{148e} measured along the columns **1004e**. In this example at least one of the length L_{148e} and the width W_{148e} tapers. For example, the lengths L_{148e} of the reliefs **148e** progressively tapers along the length of the row **1002e** such that the reliefs **148e** at one end of the row **1002e** have a first length L_{148e-1} that is greater than a second length L_{148e-2} of reliefs **148e** at other end of the row **1002e**. Additionally or alternatively, the widths W_{148e} may progressively taper along the height of each column **1004e** such that reliefs **148e** at one of a column **1004e** have a first width W_{148e-1} that is greater than a second width W_{148e-2} of reliefs **148e** at the other end of the column **1004e**. The progressive taper results in the lattice structure having an arcuate profile where both the length L_{148e} and the width W_{148e} taper, as shown in FIG. 11E. The lattice structure swatch **1000e** may include foamed and unfoamed materials.

As set forth above, any combination of the lattice structures shown in the lattice structure swatches **1000a-1000e** may be incorporated in a single compressible component **136-136b**. Additionally, different areas of a compressible component **136-136b** may include different materials. Compressible components according to the present disclosure may be constructed using additive manufacturing methods (i.e., three-dimensional printing) to achieve complex and variable geometries. Furthermore, the use of additive manufacturing allows the use of different materials within a single lattice structure, and allows for different areas of the lattice structure to be uniquely tuned by adjusting lattice thicknesses as well as sizes, shapes, and orientations of reliefs.

Turning now to FIGS. 12A-12C, an example method for constructing the adjustment element **130** discussed previously is provided. While FIGS. 12A and 12B illustrate the compressible component **136** including the adjustment zones **150a-150c**, similar principles would be applied in manufacturing the other adjustment elements **130a-130c** discussed herein. Here, each adjustment zone **150a-150c** includes a lattice structure **146** having staggered parallelogram configuration. Thus, the first adjustment zone **150a** includes a first and second reliefs **148a, 148b** having lengths oriented across a width of the compressible component **136**, the second adjustment zone **150b** includes first and second reliefs **148a, 148b** having lengths oriented along a length of the compressible component **136**, and the third adjustment zone **150c** includes first and second reliefs **148a, 148b** having lengths extending across the width of the compressible component **136**. As provided previously, the compressible component **136** may be formed using an additive manufacturing process.

In FIG. 12C, the compressible component **136** is shown disposed between the inner barrier layer **140a** and the outer barrier layer **140b**. Opposing surfaces of the inner barrier layer **140a** and the outer barrier layer **140b** are joined to each around the periphery of the compressible component **136** to seal the compressible component **136** within an interior void **134** formed between the barrier layers **140a, 140b**. Once formed, the adjustment element **130** can be incorporated into an upper **100**, either by attaching the adjustment element **130**

16

to an underlying substrate (e.g., the bootie **120**) or by forming the upper **100** of the adjustment element **130**.

The following Clauses provide an exemplary configuration for an adjustment element for an article of footwear and an article of footwear described above.

Clause 1. An adjustment element for an article of footwear, the adjustment element comprising a bladder including a barrier layer defining an interior void and a compressible component disposed within the interior void and including a lattice structure defining a plurality of reliefs formed in the lattice structure, the compressible component operable between an expanded state when the interior void includes a first pressure and a contracted state when the interior void includes a second pressure.

Clause 2. The adjustment element of Clause 1, wherein reliefs are parallelogram-shaped and extend through a thickness of the compressible component.

Clause 3. The adjustment element of any of the preceding Clauses, wherein the lattice structure defines a first adjustment zone including a first plurality of reliefs oriented in a first direction and a second adjustment zone including a plurality of reliefs oriented in a second direction different from the first direction.

Clause 4. The adjustment element of any of the preceding Clauses, wherein the compressible component includes a resilient polymeric material.

Clause 5. The adjustment element of Clause 4, wherein the resilient polymeric material is a foam material.

Clause 6. The adjustment element of any of the preceding Clauses, further comprising a port connected to the barrier layer and providing fluid communication between the interior void and a variable pressure source.

Clause 7. The adjustment element of any of the preceding Clauses, wherein the first pressure is equal to or greater than ambient pressure and the second pressure is less than ambient pressure.

Clause 8. The adjustment element of any of the preceding Clauses, wherein the adjustment element includes an interior seam separating the bladder into a first chamber and a second chamber.

Clause 9. The adjustment element of any of the preceding Clauses, wherein the adjustment element forms an upper of an article of footwear.

Clause 10. The adjustment element of Clause 9, wherein the compressible component includes a first plurality of the reliefs operable to contract in a first direction in a forefoot region of the upper and a second plurality of the reliefs operable to contract in a second direction in a mid-foot region of the upper.

Clause 11. An article of footwear comprising a bootie defining an interior void, and an adjustment element attached to the bootie and including a bladder having a barrier layer defining an interior void and a compressible component disposed within the interior void, the compressible component including a lattice structure defining a plurality of reliefs formed in the lattice structure, the compressible component operable between an expanded state when the interior void includes a first pressure and a contracted state when the interior void includes a second pressure.

Clause 12. The article of footwear of Clause 11, wherein reliefs are parallelogram-shaped and extend through a thickness of the compressible component.

Clause 13. The article of footwear of any of the preceding Clauses, wherein the lattice structure defines a first adjustment zone including a first plurality of the reliefs oriented in a first direction and a second adjustment zone including a

17

second plurality of the reliefs oriented in a second direction different from the first direction.

Clause 14. The article of footwear of Clause 13, wherein the first plurality of the reliefs are operable to contract in a first direction in a forefoot region and the second plurality of the reliefs are operable to contract in a second direction in a mid-foot region.

Clause 15. The article of footwear of any of the preceding Clauses, wherein the compressible component includes a resilient polymeric material.

Clause 16. The article of footwear of Clause 15, wherein the resilient polymeric material is a foam material.

Clause 17. The article of footwear of any of the preceding Clauses, further comprising a port connected to the barrier layer and providing fluid communication between the interior void and a variable pressure source.

Clause 18. The article of footwear of any of the preceding Clauses, wherein the first pressure is equal to or greater than ambient pressure and the second pressure is less than ambient pressure.

Clause 19. The article of footwear of any of the preceding Clauses, wherein the adjustment element includes an interior seam separating the bladder into a first chamber and a second chamber.

Clause 20. The article of footwear of any of the preceding Clauses, wherein the bootie is exposed along a throat region of the article of footwear.

The foregoing description has been provided for purposes of illustration and description. It is not intended to be exhaustive or to limit the disclosure. Individual elements or features of a particular configuration are generally not limited to that particular configuration, but, where applicable, are interchangeable and can be used in a selected configuration, even if not specifically shown or described. The same may also be varied in many ways. Such variations are not to be regarded as a departure from the disclosure, and all such modifications are intended to be included within the scope of the disclosure.

What is claimed is:

1. An adjustment element forming an upper of an article of footwear, the adjustment element comprising:
 a bladder including a barrier layer defining an interior void; and
 a compressible component disposed within the interior void and including a foam lattice structure defining a plurality of reliefs formed in the lattice structure, a first plurality of the reliefs operable to contract in a first direction in a forefoot region of the upper and a second plurality of the reliefs operable to contract in a second direction in a mid-foot region of the upper, wherein the compressible component operates between an expanded state when the interior void includes a first pressure and a contracted state when the interior void includes a second pressure less than ambient pressure.

18

2. The adjustment element of claim 1, wherein reliefs of the plurality of reliefs are parallelogram-shaped and extend through a thickness of the compressible component.

3. The adjustment element of claim 1, wherein the lattice structure defines a first adjustment zone including the first plurality of reliefs oriented in the first direction and a second adjustment zone including the second plurality of reliefs oriented in the second direction different from the first direction.

10 4. The adjustment element of claim 1, further comprising a port connected to the barrier layer and providing fluid communication between the interior void and a variable pressure source.

15 5. The adjustment element of claim 1, wherein the first pressure is equal to or greater than ambient pressure.

6. The adjustment element of claim 1, wherein the adjustment element includes an interior seam separating the bladder into a first chamber and a second chamber.

20 7. An article of footwear comprising:
 a bootie defining an interior void, and
 an adjustment element attached to the bootie and including a bladder having a barrier layer defining an interior void and a compressible component disposed within the interior void, the compressible component including a foam lattice structure defining a plurality of reliefs formed in the lattice structure, a first adjustment zone including a first plurality of the reliefs oriented in a first direction and operable to contract in the first direction in a forefoot region, and a second adjustment zone including a second plurality of the reliefs oriented in a second direction different from the first direction and operable to contract in the second direction in a mid-foot region, wherein the compressible component operates between an expanded state when the interior void includes a first pressure and a contracted state when the interior void includes a second pressure less than ambient pressure.

35 8. The article of footwear of claim 7, wherein reliefs of the plurality of reliefs are parallelogram-shaped and extend through a thickness of the compressible component.

30 9. The article of footwear of claim 7, further comprising a port connected to the barrier layer and providing fluid communication between the interior void and a variable pressure source.

40 10. The article of footwear of claim 7, wherein the first pressure is equal to or greater than ambient pressure.

45 11. The article of footwear of claim 7, wherein the adjustment element includes an interior seam separating the bladder into a first chamber and a second chamber.

50 12. The article of footwear of claim 7, wherein the bootie is exposed along a throat region of the article of footwear.
